UNITED STATES PATENT OFFICE.

GEORGE H. CLARK, OF BOSTON, MASSACHUSETTS.

SHOE-FORM.

No. 877,049.

Specification of Letters Patent.

Patented Jan. 21, 1908.

Application filed July 3, 1903. Serial No. 164,105.

To all whom it may concern:

Be it known that I, GEORGE H. CLARK, of Boston, county of Suffolk, State of Massachusetts, have invented an Improvement in 5 Shoe-Forms, of which the following description, in connection with the accompanying drawings, is a specification, like characters on the drawings representing like parts.

This invention relates to shoe forms adapted to be used for holding a shoe while it is being finished, polished, ironed, or displayed although it is obvious that it may be used to hold a shoe in any part of the process of making the same.

15 The invention consists in a divided shoe-form comprising in combination a fore-part and a rear part which are held together with a rocking and sliding joint by means of a spring-connector, and constructed to support the shank of a shoe and release the vamp-seam of such shoe when the form is bent or crippled for the purpose of being withdrawn from the latter.

Figure 1 shows in side elevation a shoe 25 form embodying this invention. Fig. 2 is a vertical section of the shoe form. Fig. 3 is a sectional detail of a portion of the form showing the fore-part in the abnormal position, it will occupy when the shoe is being withdrawn, the front end of the heel part having dropped below the top of the fore-part at the ball line to thereby materially reduce the ball measurement.

30 *a* represents the heel-part of the transversely divided shoe form, and *b* the fore-part. The heel-part *a* extends from the heel to approximately the ball line of the form, and is recessed upon its under side, at its front end, to provide a forward extension *a'* which is formed with an outwardly curved 35 engaging face *a²* near its extremity. The fore-part *b* is recessed upon its upper side at its rear end, to receive the forward extension *a'* of the heel-part, and also to provide a rearward extension which enters and fills the recess formed in said heel-part. In making 40 the form and providing the extensions and recesses aforesaid, the fore-part is merely separated from the heel-part on a line 2 which extends from the top of the form, at a 45 point approximately opposite the ball and at or about the position of the vamp-seam of a shoe in a rearward direction to a point near the middle of the shank, or in other words, 50 from the top of the ball line to about the middle of the shank, the line of severance

being shown as curved, although it is not essential that it should be curved precisely as shown, although it is essential that the curvature should be such that an outwardly curved engaging face *a²* is formed on the forward extension *a'* of the heel-part near its extremity, and that the recess in the fore-part at this point should be correspondingly formed. The line of severance as herein shown crosses the waist line of the form at a point approximately midway its length, said waist line being indicated by dotted lines 20.

By providing the forward extension *a'* with an outwardly curved engaging face, it will be seen that the parts *a* and *b* when moved one with relation to the other will move on said engaging face as a pivot, as shown in Fig. 3, and that when thus moved the end of the forward extension *a'* on the heel part will drop below the top of the fore-part and the ball measurement will be thus materially reduced. If the heel-part is held stationary the fore-part will be moved relative to the heel-part, as the shoe is withdrawn, the forward end of the fore-part moving upward, and if the heel-part is not so held, and the form is withdrawn from the shoe the rear end of the heel-part will be moved upward as the form is withdrawn; but in either instance the important result sought for is obtained, viz.: the reduction of the ball measurement by dropping the forward end of the heel-part below the fore-part at the top of the ball line, or thereabouts. Reducing the measurement of the form at this point enables the shoe to be easily withdrawn without straining, cracking, tearing or wrinkling the vamp, and without breaking or wrinkling the shank. The portion of the fore part which extends to about the middle of the shank, as indicated in the drawings, serves to sustain the shank of a shoe against injury or breakage under the strain which is applied in causing the form to bend or cripple as indicated in Fig. 3 of the drawings.

Producing the forward extension *a'* and its curved engaging face *a²* by merely severing the parts *a* and *b*, results in producing a form which, when the parts occupy their proper relative positions, will present a perfectly smooth surface, so that a shoe placed thereon may be worked upon with an iron, brush or other implement.

The abutting faces of the fore-part and body portion are socketed, as at 3, said sockets being disposed opposite each other, and

a spiral spring 4 is contained in said sockets, the ends of which are connected to the respective parts of the form at the bottoms of the sockets or thereabouts. The entrances 5 to the sockets 3 are elongated, or made large enough to provide a suitable working space for the spring as the fore-part moves relatively to the body portion.

The spring forms an elastic connection between the fore-part and body portion, so that the one may be moved with respect to the other, and also separated for a short distance as may be required, and thereafter restored to its normal position. At the line of severance, both at the top and bottom of the form, a hole is bored in the form, and into said holes dowel pins 5 are secured, which will be retained in place in connection with one of the members of the form, and serve as a guide for the other member; and also in the body portion a hole is bored into which a dowel pin 10 is secured, the end of which is beveled and projects into a hole in the fore-part, said hole being made of suitable size and shape to receive it. After the shoe has been withdrawn the spring connection restores the fore-part to its normal position.

Claims.

1. A shoe-form comprising two parts meeting in a joint extending from a point over the ball to near the middle of the shank, and a spring-connector holding their meeting surfaces together and permitting such surfaces to rock and also slide on each other 35 when the form is bent or crippled.

2. A shoe-form comprising two parts meeting in a joint extending from a point over the ball to near the middle of the shank, and a spring-connector holding their meeting surfaces together and permitting such surfaces to rock and also slide on each other when the form is bent or crippled, the said parts being constructed to support the shank and release the vamp-seam while the form is bent or crippled for the purpose of being withdrawn from a shoe.

3. A shoe-form comprising two parts meet-

ing in a point extending from a point over the ball to near the middle of the shank, the fore-part having a hole therein entering from its meeting surface, and the heel-part having a projecting dowel with beveled end which enters the said hole, and a spring-connector holding the meeting-surfaces of said parts together and permitting such surfaces to rock and also slide on each other when the form is bent or crippled.

4. A shoe-form comprising, essentially, a heel-part, a fore-part, and a spring-connector, and having the meeting portions of the said heel-part and fore-part overlapped horizontally, with the forward portion of the heel-part overlying the rearward portion of the fore-part, and having the two parts fitted together along a compound curve beginning at the top of the form at or about the place of the vamp-seam of a shoe and extending in an oblique direction rearward and downward through the waist-portion and terminating at the under side of the form at or about the middle of the length of the shank.

5. A shoe-form comprising, essentially, a heel-part, a fore-part, and a spring-connector, having the meeting portions of said heel-part and fore-part overlapped horizontally and the forward extension of the heel-part overlying the rearward portion of the fore-part, with the said forward extension formed with an outwardly curved engaging face near its extremity and the fore-part recessed upon its upper side at its rear end to receive the said face and also provide a rearward extension which enters and fills a recess formed in said heel-part, and having the two parts fitted together along a line beginning at the top of the form at or about the place of the vamp-seam of a shoe.

In testimony whereof, I have signed my name to this specification, in the presence of two subscribing witnesses.

GEO. H. CLARK.
